KNITTING MACHINE

Ferdinand Klumpp, Weehawken Township, Hudson County, and Fritz Lambach, Belleville Township, Essex County, N. J., assignors, by mesne assignments, to Robert Reiner, Incorporated, Weehawken, N. J., a corporation of New Jersey

Application August 18, 1937, Serial No. 159,642

24 Claims. (Cl. 66—84)

This invention relates generally to improvements in knitting machines and particularly to that class thereof by which novel knitted and textile fabric comprising knitting warp with an inlaid filler can be manufactured. A machine made in accordance with this invention also may be employed as a warp knitting machine for conventional knitting or as a warp knitting machine wherein filler threads are introduced into the fabric as it is being produced.

This application includes modifications and improvements over our copending application, Serial No. 49,453, filed November 13, 1935, for Knitting machines.

The knitting machine contemplated by this invention is provided with novel filler laying instrumentalities cooperating with the knitting facilities for producing a fabric comprising filler threads (which may extend either from selvedge to selvedge or partly through the fabric and which may be present in any desired courses of the warp threads) enveloped by knitting loops or chains of warp threads, the filler threads connecting with the knitted rows thereby preventing both longitudinal and transverse stretching and in general distortion of the fabric. The machine provides means for introducing a warp into the fabric for interconnecting, respectively, two or more knitted loops or connecting-links of adjacent rows or courses, which both strengthens the fabric and extends the range of varied design or pattern possibilities.

One or more filler threads or yarns may be laid in each course of the warp and by employing yarns or threads of different colors for the fillers and warps various desired designs and color effects of fabric may be obtained. The filler may be either of a knitted or an unknitted construction or of any other suitable construction.

An object of the present invention is to provide in a knitting machine novel, efficient and effective means for feeding, carrying, laying and controlling the distribution of filler thread in desired courses of a knitting fabric.

A further object of this invention is to provide improved means for coordinating, determining and controlling the movements of the warp guide fingers units in their relation to the knitting needles and filler feeding, controlling and laying mechanisms.

It is a further object of the present invention to provide means for incorporating a plurality of filler threads of different extent through the width of the fabric.

For facilitating the carrying out some of the provisions and objects herein, other objects of this invention are:

To provide for the feeding of filler thread or yarn to and introducing or laying the same into the fabric as it is being knitted, by having a filler carrier selectively connectable with and disconnectable from a flexible transmission band to which is imparted a non-uniform reciprocating motion, the extent of which motion being variable and regulatable.

To provide for interrupting the laying of the filler at predetermined intervals, during the continuous running of the machine.

To provide friction brake means for arresting the motion of said band.

To provide a movable bank of projections or sinkers which may be of the same or different lengths capable of receiving the filler thread directly from the carrier, of positioning the same adjacent the needles and of acting upon a preceding laid filler thread to press the same downwardly.

To provide for the simultaneous use of more than one filler carrier for simultaneously feeding a plurality of filler threads to incorporate the same in separate fabrics being simultaneously produced by the machine.

A further object of this invention is to so coordinate the instrumentalities attaining objects hereinabove mentioned, that pattern or design composition and strength of fabric may be obtained to a far greater degree and extent than heretofore.

In a straight or flat knitting machine stitch formation is effected through cooperation between the vertical reciprocating movement of the latch-needle bank and the shiftable oscillating (looping) movements of the warp feeding guide fingers.

The pattern effects are predetermined by the selective shiftable movement of the guide fingers which may carry yarns or threads of the same or different colors across one or more of the hooks of the needles, in accordance with a predetermined fashion to produce the desired pattern or design. For this purpose a needle bank is substantially vertically reciprocated relative to a face plate against which it slides.

Where two needle banks are employed they are slightly sloped toward each other to bring the needle hooks close together and the face-plates against which the needles slide are spaced apart providing room for passage of the knitted fabric. The warp yarn or thread is directed and presented to the bank of latch-needles by the guide

fingers of which there may be several units to accommodate different yarns or threads as desired. The reciprocation of the needle bank is determined by a cam. The oscillating movement of the warp guide fingers units is controlled by cams. The shiftable or endwise movements of the warp guide fingers units are respectively controlled by individual pattern chains made up of special, interchangeable cam links. The cooperation of the above various instrumentalities exists in a standard form of straight knitting machine. This invention deals, in part, with improved novel means for coordinating, regulating and controlling the movements of these instrumentalities in their mutual relation and in their relation to filling-weft feeding controlling and laying mechanisms.

According to this invention one or more carriers, to each of which is imparted a controllable non-uniform reciprocating movement, feeds filler threads or yarns directly to a movable bank of sinkers which support and lay the same relatively between (1) a connecting link (coming from a preceding loop) and a succeeding loop of the same course as the connecting link and (2) a succeeding loop of a succeeding course which is carried through the said connecting link and supported thereby. The movable bank of sinkers or projections are adapted to receive the filler thread directly from the carrier and position the same adjacent the needles. One or more of these filler threads may be laid in each course and by the use of more than one carrier, fillers different in quality or color may be laid in the same or different courses. The extent of the movements of the carriers are controlled so that the fillers, if desired, may be extended only partly through and may be varied with respect to the width of the fabric. Active and inactive periods of the carriers are controlled in a predetermined manner by a pattern chain made up of special, interchangeable cam links trained on the same drum as the pattern chain controlling the movements of the warp feeding guide fingers bars or units.

A plurality of simultaneously operable carriers are provided for feeding a plurality of weft threads adjacent the needles to respectively incorporate the same in separate fabrics simultaneously produced by the machine.

Certain of the warp feeding guide fingers may be controlled so that if desired the warp threads fed thereby may not enter into the knitting operation but are incorporated unknitted in the fabric during the knitting operation and the laying of the filler and may interconnect two or more knitted loops or connecting links of adjacent rows or courses. This unknit warp is referred to herein as an unknit warp, and the warp forming the stitch or loop as the knitting-warp.

It is easily understood from the above that in accordance with our invention a fabric can be made having different and or uniform sections or parts of elastic and non-elastic properties produced by the employment of threads or yarn having suitable characteristics.

The disclosure made the basis of exemplifying the present inventive concepts suggest practical embodiments thereof, but the invention is not to be restricted to the exact details of this disclosure, and the latter, therefore, is to be understood from an illustrative rather than a restrictive standpoint.

The foregoing and other objects, purposes and

advantages may be attained by the novel design, construction and arrangement of parts, as hereinafter described and illustrated in the accompanying drawings, constituting a feature of 5 the disclosure, and in which:

Fig. 21 is a fragmentary view of a knitted filler construction or strand employable in the fabric 55 produced by the machine.

In the illustrated embodiment of the invention, the frame of the machine comprises the end frames 25 and 26 held in rigid spaced relation by a front tie member 27, a rear tie member 28, and an upper centrally disposed tie member 29.

Each of the end frames (Figs. 1, 2, 3) is 60 preferably fitted with brackets such as 30 which serve to support stanchions 31. These, in pairs, are arranged to adjustably carry longitudinal tubes or rods 32 upon which are supported transversely disposed notched bars 33. The notches 34 of these bars, which may be adjustably positioned on the tubes 32, serve as bearings for the trunnions 35 of the warp yarn or thread beams 36.

In the present instance, each beam 36 is provided with a brake drum 37 around which is trained a brakeband 38 having one end fixed at 70 39 to a bracket 40 which is also supported on a

cross bar 33, and having its other end connected as to a coil spring 41 which in turn is adjustably carried by said bracket as at 42. In this manner a varied tension may be applied to the brake drum, and thus a suitable drag is applied to the beam. It will be noted that this arrangement obviates the use of cumbersome counterweights and other types of drags and, as a whole, the above described arrangement of the warp beams provides an efficient and flexible clean-cut arrangement.

The motive power of the machine is provided by an electric motor or the like M, the drive pinion 44 of which drives the gear train 45, 46, 47 and 48 mounted in any convenient manner and as best seen in Fig. 2. The gear 45 is mounted upon the main camshaft 49 and is in mesh with the gear 46 on the hand control shaft 50 which is provided with a suitable number of hand wheels 51, (Fig. 3). Similarly, through the medium of the gear 47, the gear 45 connects with the gear 48 on the longitudinally disposed shaft 52 on the opposite side of the machine from that of the main camshaft 49. This shaft 52 also carries a number of hand wheels 53, (Fig. 1). In the above manner the camshaft 49 may be rotated by the motor M or, when the motor is inoperative, by either of the hand control shafts 50 or 52.

As seen in Fig. 3, the camshaft 49 may be geared as at 54 to a vertical shaft 55, supported by brackets 56 and 56^a. The upper end of this shaft preferably carries a cam-like gear 57 which is arranged to intermittently rotate a pin gear 58, (shown in detail in Fig. 3^a) on a transverse shaft 59. This shaft is suitably carried by a bracket 60 fixed to the frame end and supports a pattern chain drum 61 (Fig. 4) which in this manner, is intermittently advanced to perform functions later described.

The camshaft 49 is also geared as at 62 to a cross shaft 63 supported in brackets 64, also carried by the frame end 26. Upon the shaft 63 is carried a cam-disk 65, the cam groove 65^a of which controls through the medium of a cam follower 65^b, the movement of an arm 66 pivoted at 67 to a bracket 68. Adjustably arranged with and carried by the arm 66 is a downwardly extending element 69^a to which is pivotally attached a link 69 connected to one end of a walking beam 70. This beam 70 is adapted to be selectively pivoted as at 71 to change the extent of movement of the other end of said walking beam. Said last mentioned end of the walking beam 70 is pivotally connected at 72^a through the rod 72 with a gear rack 73 guided for vertical reciprocation in the guide way 74, (see Figs. 4 and 5).

The reciprocatory movement of the rack 73 is utilized to impart oscillatory movement to the drum 75 through the medium of a gear train comprising the rack pinion 76, idler gear 77, and drum pinion 78. A complementary idler drum 79 is provided at the opposite end of the machine (Fig. 1) and around both drums 75 and 79 is trained an endless band 80 provided with uniformly spaced holes 81, (Fig. 5).

During the dwell or inertia period of the cam-disk 65 and, hence, during the inertia period of the band 80, a brake shoe 82 is arranged to contact a brake drum 83 on the drum 75. A cam 84 on the shaft 63, through the medium of a rock arm 85 (pivoted at 85^a) and a connecting link 86, serves to disengage the brake shoe 82 from the brake drum 83 to free the band 80 for movement under the urgency of the cam-disk 65.

From the foregoing it will be apparent that the cam 65 imparts a reciprocatory motion to the horizontal portions of the band 80 in proportion to the degree of movement imparted to the rack 73 by the walking beam 70. The greater the arc of travel of the right hand end (Fig. 3) of the walking beam, the greater the reciprocatory stroke of the band. Hence, the filler thread, which through mechanism later described, is laid in exactly the desired manner and in relation to the desired number of knitted courses.

The knitting instrumentalities of the machine are best seen in Fig. 8. A needle bar 87 carrying a multiplicity of latch needles 88, is preferably mounted on a plurality of rods 89 guided in sleeve bearings 90 carried by the machine frame. The needle bar 87 is arranged longitudinally of the machine and is disposed at a slight angle to a vertical plane, thus, the needles which are arranged to one side of the longitudinal center of the machine may be moved upward and, at their uppermost position, intersect said longitudinal center. A fixed face plate 91 is provided to guide and protect the needles and it is against this plate that the needle bar 87 slides in its reciprocating movement. It is understood that further needles (not shown) may be arranged in a similar manner on rods 89^a and on the opposite side of the longitudinal center of the machine for cooperation with the aforesaid needles 88.

Each rod 89, at its lower end, is preferably provided with a bracket 92 (Figs. 4, 5, 6, and 7) to which is pivoted a link 93, pivotally and adjustably carried by one end 94 of a bell crank lever pivoted at 95. The other end 96 of said lever is provided with a cam follower for engagement with a cam 97 on the camshaft 49. A plurality of such arrangements are provided to impart to the needle bar the contemplated substantially vertical reciprocatory movement.

The looper bars 98, in number suitable for a particular knitting operation, each carry a plurality of loopers 99 for guiding the warp threads to the knitting course, (Fig. 8). These looper bars are carried by a rock shaft 100 extending longitudinally of the machine. The looper bars 98 are adapted to be rocked around a horizontal axis and transversely of the machine by the following mechanism shown in Fig. 2.

A cam 101 is provided on the camshaft 49, and a reciprocating pitman 102 engaged with said cam is adjustably connected to an arm 103 clamped as at 103^a to the rock shaft 100. Handle means such as shown at 104 may be effectively employed in adjusting the parts so that proper oscillation is imparted to the rock-shaft 100. In addition, the pitman may be varied in length as by means shown at 105 in order to render the adjustments more flexible.

The means for supporting the looper bars 98 from the rockshaft 100 comprises a plurality of hanger brackets 106 on the rockshaft 100, each of which is provided with adjustable guide eyes 107 engaged by pins 108 carried by the respective looper bars 98, (Fig. 4). In order to steady said bars, each is provided with an upwardly extending arm 109, each slotted at 110 for engagement over a pin 111 carried by extensions 112 of a bracket fixed on the rockshaft 100.

It will be also noted that in addition to the previously described rocking movement of the looper bars around the axis of the rockshaft 100, the looper bars also are arranged to be longitudinally moved in accordance with the arrows R shown in Fig. 4. This is accomplished through

the medium of slides 113 provided with end plates 114. The slides are arranged to be moved as hereinafter described and each plate 114 is adapted to be engaged by an adjustable screw 115 carried by a respective looper bar 98. Thus as seen in Fig. 4, movement of the slide 113 to the right will cause similar movement of the associated looper bar. A spring 116, connected between each extending arm 109 and a segmental bracket 117 carried by the rockshaft, serves to effect movement to the left of the looper bar. From the foregoing it may be seen that the loopers 99 may be moved transversely of the needle bank and also longitudinally thereto.

Also necessary to the knitting functions are the filler sinkers 118 alternately arranged with the needles and adapted to be reciprocated in a horizontal plane and transversely of the machine by the following mechanism.

Cams 119 on the camshaft 49, (Fig. 1), are designed to engage and move the arms 120 of bell crank levers also pivoted at 95. The other arms 121 of the bell crank levers are connected by means of links 122 to arms 123 of other bell crank levers pivoted at 124. (Fig. 8). These second levers are formed with arms 125 which are forked as at 126 for blocks 127 carried by slides 128 movable in guides 129. The guides are preferably carried by a longitudinal structural member 130 forming part of the machine frame. The inner ends of the slides 128 are arranged to carry a sinker bar 131 which serves to support the sinkers 118 above mentioned.

The ends of the warp yarns A are brought from the beams 36, (Fig. 1) over the resiliently mounted tubes 132 and through the loopers 99 to a point above the face plate 91 where the knitting of the fabric occurs. The type and design of the knitted fabric is controlled by the endwise movement of the looper bars 98 and thus of the loopers 99. This endwise movement is accomplished by the slides 113 which are moved by the pattern cam links 133 arranged in grooves 134 in the chain drum 61, (Figs. 1 and 4). Thus, as viewed from the rear of the machine, a relatively high pattern link will urge its respective looper bar 98 towards the right and a relatively low pattern link will permit the spring 116 to move said looper bar towards the left. Hence, the makeup of the pattern chains, controlling the movement of the looper bars, control the type and design of the knitted fabrics.

The actual knitting operation will be later described in order to present a more complete picture of the flexibility of use of the machine.

The present knitting machine is designed to provide the material which is being knitted with a filler thread. In the present embodiment of the machine the reciprocatory movement of the band 80 is utilized to operate a filler carrier under control of a servo-motor for laying in the filler thread at each desired course of knitting. The mechanism and instrumentalities for performing this function are best shown in Figs. 3, 4, 6, 8, 9, 10.

The filler thread carrier comprises a carriage 135, (Figs. 9 and 10) guided for movement along the bars 136 longitudinally supported in the machine frame. The carriage 135 is arranged to be coupled selectively with either or both filler thread carriers 137 and 138. If only one filler thread is to be used, only one carrier is used as can be well understood.

The carriers are arranged to slide along respective rods 139, 140, each disposed above and

in parallel relation to the bars 136. Each carrier is provided with respective extensions 141 and 142, each further guided by rods 143, and terminating in the respective tubes 144 and 145. As is apparent, the tubes are arranged to be adjacent to and to move along and slightly above the knitting course.

The carriage 135, (Figs. 8 and 9) is fixed to the band 80 as by means of screws or the like 146 and hence the carriage moves bodily with said band. The carriage, for each carrier, is provided with a pivoted latch member 147 which is adapted to engage in a notch 148^a in each carrier. A spring 148 is used to hold the latch in its respective notch. Each latch 147 is formed with an upstanding projection 149 which is engaged with a fork 150 of a tilt lever 151 pivoted at 152 to the carriage. Hence, as seen in Fig. 9, movement of the fork 150 to the left will cause the latch 147 to become uncoupled from the carrier 138 and therefore said carrier will not be moved with the carriage. Opposite movement of the fork will similarly unlatch the carrier 137.

In order to maintain an unlatched carrier in nondisplaceable position, each of the rods 139 and 140, at both ends thereof, is provided with spring latches 152^a engageable in notches 153 in the carriers and because of the rapidity of the movement of the carriage, buffer springs 154 may be provided to counteract the moments of inertia of the carriers at the end of the movement of stroke.

The selection of movement of the fork 150 and the power for performing this function are best illustrated in Figs. 4 and 6. One of the slides 113 and designated 113^a, is associated with a cam link chain 133 on the drum 61. A spring 155 is used to maintain this slide in contact with the chain links which like those previously described, are of varying heights.

As shown, the slide 113^a, is provided with a pin 156 engaged in the fork 157 of the arm 158 pivoted at 159. The arm 158 forms a bell crank with another arm 160 which is also provided with a fork 161, (Fig. 6). The last mentioned fork is engaged over a lever 162 pivoted for horizontal movement at 163 to a bracket 164 on the rockshaft 165. The lever 162, at its free end is also provided with a fork 166 and in its normal and neutral position, this fork is occupied by a fixed projection 167.

From the above description, it is apparent that a high cam link will move the slide 113^a to cause the arm 160, (through members 166-169 inclusive), and thus the lever 162, to swing towards the left, and that the spring 155, when a low cam link is opposite the slide, will cause the lever 162 to move towards the right. Similarly, a cam link of intermediate height will position the lever 162 at the neutral position shown. The above mechanism forms the selection means above indicated.

When the lever 162 is swung, its fork 166 becomes engaged over either pin 168 or pin 169 respectively carried by vertically disposed rods 170 and 171 guided for vertical movement in brackets 172 and 173. At their lower ends, these rods are respectively engaged with cams 174 and 175 on the camshaft 49, cam followers, such as 176 being provided for the purpose. As shown, springs 177 may be employed for controlling the movement of the rods 170 and 171 as imparted by the mentioned cams 174 and 175.

Now it can be seen, that with the forked lever 162 engaged with the pin 168, the cam 174, which

is provided with a relatively high cam portion, will move the rod 170 up to rock the shaft 165 in a clockwise direction as seen in Figs. 6 and 9. Hence, the curved levers 178, which are carried by the rockshaft 165 will, through the medium of tapered pins 179 carried on their free ends, engage the fork 180 on the upper end of the tilt lever 151 to uncouple the carrier 138 as previously described. Similarly, with the forked lever 162 engaged with the pin 169, the cam 175, which is provided with a relatively low cam portion, will cause movement of the rod 171 down to rock the shaft 165 in a counterclockwise direction. This movement of the rockshaft, in the manner above set forth, will cause the uncoupling of the carrier 138.

Since it is desired to uncouple the carriers only at the ends of the carriage stroke, the curved arms 178 and their tapered pins 179 are positioned at each end of the said stroke. Therefore, once the carriage starts its movement with or without a carrier, this condition will be maintained until the stroke is completed.

The flexibility of the above described arrangement should be readily apparent. For instance, one or more filler threads may be laid with each course of knitting. Under that condition the carriers would never be uncoupled from the carriage 135. Either of two things may be done to accomplish this. The chain on the drum 61 may comprise only links of intermediate height so that the slide 113^a has no movement imparted to it and, hence, the movements of the rods 170 and 171 effect no movement of the rockshaft 165; or the curved arms 178 may be removed so the latches 147 are not acted upon. Also, one carrier may remain coupled so as to lay a filler thread with each knitting course, and the other carrier periodically coupled and uncoupled to lay a second filler at every two, three, four, or more courses. Further, the cam link chain controlling the coupling and uncoupling of the carriers may be so arranged as to lay two different kinds of colors of filler threads alternately or in any relation to suit the tastes of the designer of the fabric to be produced.

Up to this point of the specification, there has been disclosed means for knitting a fabric in varying designs with or without one or more filler threads. As will be apparent from (Figs. 19 and 20), additional unknitted warp threads may be incorporated in the fabric by bringing them to the knitting course between the needles. Still greater flexibility of design is afforded in this manner.

While the foregoing is descriptive of means for knitting a fabric with one bank 87 of needles, it is apparent that two banks 87 may be used to provide a fabric of different character. In this event, a duplicate needle bar may be mounted on the rods 89^a and associated with another face plate such as 91, the knitted material being adapted to pass between the face plates and to be suitably taken up on a takeup roll positioned at the bottom of the machine. In that event the feed rolls 201, 203 which maintain the fabric under suitable tension, may be carried on the shafts shown at 181^a and 182^a of Fig. 7.

However, when only one needle bank 87 is used, the feed roll shafts may be positioned in front of the face plate 91 as shown at 181 and 182. The former is intermittently driven as follows:

Upon the camshaft 49 (Fig. 2) there is provided an eccentric 183, which, through the eccentric strap 184, reciprocates the rod 185 con-

nected to the slotted end 186 of a bell crank pivoted at 187. The other arm of said bell crank carries a driving pawl 188 which is engaged with a ratchet wheel 189 mounted for rotation at 190.

The ratchet wheel 189 is preferably free on the shaft 190 which has affixed to it a handle 191 provided with detent means selectively engageable in spaced holes 192 in said ratchet wheel. Also fixed to the shaft 190 there is a pinion gear 193, which, because it is connected to the handle 191 which in turn is engaged with the ratchet wheel, is intermittently driven by the pawl 188 by reason of the eccentric 183. A ratchet pawl 194 is provided to maintain the advanced position of the ratchet wheel 189 during the recovery movement of the driving pawl.

The pinion gear 193 is mated with a gear 195 on a stub shaft 196 which also carries a sprocket wheel 197 around which is trained one bight of a chain 198 having its other bight trained around a sprocket wheel 199 on the shaft 181. If desired, an idler sprocket 200 may be employed to obviate slack in the chain 198.

Thus, each revolution of the camshaft 49, will cause advancement of the shaft 181 and its feed-roll 201 (Fig. 1) to a degree imparted by the stroke of the driving pawl 188 as controlled by the position of the end of the rod 185 in the slotted member 186. The closer to the pivot 187 that this rod end is, the smaller the advancement of the feed roll 201, and, similarly, the further from said pivot, the greater said advancement.

The roller 201, (Fig. 7) is associated with an idler roller 203 on the shaft 182 and this latter roller is preferably mounted on blocks 202 which are adapted to be adjustably positioned on ways 204 of brackets 205 which also serve to support the roller 201.

The knitted fabric is adapted to pass between the face plate 91 and the roller 201, under said roller, over the roller 203 and then downward to a take-up roll 206. The take-up roll 206 is mounted on brackets 207 and is arranged to be driven from the stub shaft 196 as follows:

The upper end of an angularly disposed shaft 208 is driven from the stub shaft as by bevel gears 209 and supported by brackets 210 and 211. The lower end of said shaft 208 is preferably geared, as at 212, to a horizontally disposed stub shaft 213. It is preferred to drive this stub shaft at a greater intermittent speed than the feed rolls 201 and 203 and hence the gear on said stub shaft 213 is somewhat smaller than the mating gear on the shaft 208.

This overdrive is necessary so that the fabric, as it is being taken up on the take-up roll 206, is kept taut. In order to accomplish this, a slip friction clutch 214, (Fig. 1) is interposed between the stub shaft 213 and the take-up roll 206. Now it can be seen that as the fabric builds up on the take-up roll more slip will occur at the clutch 214, whereas the advancement of the feed rollers will remain uniformly constant.

The motor switch "S" may be operated by either of the control shafts 215 at the front and the rear of the machine which for this purpose are linked together as at 216. At the end of one of the shafts 215, (Figs. 4 and 5) there is preferably provided a disc 217 which is provided with radially disposed abutments 218 to limit the rotational movement of the shafts 215, on extension 219 of the lever 220 which carries the brake shoe 22 having engagement with the abutments for this purpose.

In the "on" position of the control shafts 215,

the end of the extension 219 is arranged to seat in either depression 221 in the disc 217 and thus the spring 222 urges the brake shoe 82 into contact with the brake drum 83. Hence, the brake drum 83 is freed only by the high point of the cam 84 in synchronous timing with the other cams of the machine. However, when it is desired to operate the machine by hand during setting up, etc., the brake shoe 82 may be freed from contact with the brake drum 83 by placing the relatively high portion 223 of this disc 217, under the nose of the extension, 219, (Fig. 5).

When setting up the pattern drum 61 and in order to obtain clearance for positioning the cam links thereon, it is desirable to retract the slides 113 and 113^a. This may be accomplished through the medium of a hand lever 224 fixed to a pivot shaft 225 upon which are carried a plurality of down reaching arms 226. These arms preferably extend between said slides and are each arranged to contact a roller 227 carried by each adjacent slide. A detent 228, carried by the lever 224, is associated with fixed teeth or serrations 229. Thus, with the lever as shown in Fig. 4, the slides may have contact with cam links of various heights and are free to be moved endwise thereby. Moving the lever to the left so the arms 226 move the slides to the right will afford the clearance necessary for setting up the pattern drum. In this position the leftmost tooth 229 will engage the detent to hold the lever in this position.

In order to render the movement of the needle bar 87 more readily adjustable, each arm 94 is preferably provided with a slide block which may be securely set in relation to the arm pivot 95 as by means of a feed screw 231, accessible from the front of the machine, (Fig. 7).

While the machine may be set up to knit one width of fabric within its capacity, it is more often the case that two or more widths are simultaneously knitted. By employing as many carriages 135 as the number of widths of fabric desired, a plurality of identical fabrics may be formed. Here again, the flexibility of the present arrangement becomes apparent when it is pointed out that either or both the knitted warp threads and the filler threads may be freely varied.

In some instances it is desired to incorporate two filler threads of different extent through the width of the fabric, i. e., one filler thread extending for the entire width of the fabric and the other extending only through a medial portion of said fabric.

It is apparent from the above that one of the carriages must have a longer traverse than the other. In that event an arrangement such as shown in Figs. 11, 12 and 13 may be employed.

In the embodiment here illustrated, two widths of fabric F and F' are to be knitted, each to be provided with a filler thread extending through the entire width of the fabric and another filler thread through the portion of each respectively designated f and f'.

The band 80 has affixed to it a carriage 135 which may move, as before described, along guide-ways 136. This carriage may move the extension arm 141 which supports the yarn tube 144, through the medium of the latch 147, (Fig. 13). Since no means for moving the latch is provided, the reciprocatory movement of the carriage is thus transmitted to the yarn tube, hence, the filler yarn passing through said tube will be laid at each course and for the full width of the fabric F.

While another carriage similar to the carriage 135

135 may be used for laying the filler yarn for the fabric F', it is preferred to couple the extension arm 141 with a similar arm 141^a as by means of a connecting member 232. Thus the movement of the carriage 135 is imparted to said latter arm 141^a and its yarn tube 144^a will lay a filler thread in the fabric F' in a manner identical to that performed for the fabric F.

Also fixed to the band 80, there is provided a carriage 233, which is provided with a lug 234. The extent of movement of this carriage is the same as the carriage 135. At each end of the stroke of movement of its carriage, the lug 234 is adapted to alternately engage and move the respective slide collars 235 and 235^a on the fixed rod 140.

The collar 235 is backed by a coil spring 236 also strung on the rod 140, and the other end of said spring is adapted to engage against one end of a thread carrier 237, which carries an extension arm 238 provided with a yarn tube 239. The other end of the carrier is backed by a coil spring 240 similar to, but somewhat shorter, than the spring 236. A fixed collar 241 is arranged as an abutment for the spring 240. The above described mechanism is designed to lay the filler thread in the area of the fabric F which is designated f.

The filler thread for the area f' of the fabric F' is laid by the carrier 237^a, which carries the arm 238^a and yarn tube 239^a. Associated with this carrier are the coil springs 236^a and 240^a, the slide collar 235^a and fixed abutment collar 241^a. This latter assembly is similar to the one above described.

The two carriers 237 and 237^a are connected together as by a member 242. As can be seen, the carriage 233 may move between the collars 235 and 235^a without imparting any movement to the carriers 237 and 237^a, but the latter portion of each stroke of the carriage 233, will pick up and move said collars 235 and 235^a and hence the carriers so that the respective weft threads are laid in the fabrics F and F'. Thus when the carrier 237 is moved towards the left by the carriage 233, the carrier 237^a is similarly moved towards the left through the medium of the connection 242, and similarly, when the carrier 237^a is moved towards the right by said carriage, the carrier 237 is also moved towards the right through the medium of said connection means 242.

From the foregoing it can be seen that despite the fixed stroke of the band 80, which is the stroke of the carriages 135 and 233, one set of filler laying members travels one distance whereas the other set of filler laying members travels a lesser distance.

It is believed that the specification, as thus far progressed, clearly sets forth the means and mechanism for providing various types of knitted fabric as contemplated in this invention. The following description will deal with the mode of operation of the machine.

Operation

Figures 14 to 17, inclusive, indicate in semi-diagrammatic form, several steps in the knitting operation as associated with the filler laying operation of a carriage such as shown in Figures 9 and 10, it being assumed that the movement of said carriage is for the entire width of the fabric to be knitted. It is also assumed that only one of the carriers 137 or 138 is to be used. In this instance the inner carrier 138 will be

employed. It is further assumed that the carriage 135 is at the left end of its stroke.

Several courses of fabric having been already knitted as shown in Figure 14, the needles 88 are at their lowermost position and the fabric is supported on them by means of the loops A¹ formed in the warp threads A. The sinkers 118 are retracted and the tube 145 is disposed so as to deposit the filler thread B upon the upper edges of said sinker. Now, the sinkers are moved to the right (Figure 15) so that the shoulders 118^a of the sinkers move the laid filler thread to the right of the needles. In this condition the tube 145 has moved to a point beyond the needle bank so that the needles may now be moved upward.

This latter condition is shown in Figure 16, the loops A¹ having opened the latches of the needle as shown. The filler thread is now positioned between the needles and the oncoming warp yarn A. The loops 99 now move from a position to the right of the needles to a position to their left, preparatory to forming new loops A² immediately beneath the needle hooks and around the needles. The compound rocking and oscillatory movement of the loopers serve to first move the warp threads between the needles to the position shown in Figure 16 and then back in one of the directions shown by the two-head arrow 243 (Fig. 18) so that the threads are passed around the needles. As the loopers are rocked back to the position shown in Figure 17 the loops A² are formed. It will be now seen that the filler thread B is disposed between the loops A¹ and A². As the needles are moved down and the sinkers are again withdrawn, the loops A¹, which had previously been pulled free of the needle latches by the pull exerted on the knitted fabric, now lift the latches to close them. These loops will now slip off the end of the needles which now support the loops A². From the position shown in Figure 17, the parts move to the position of Figure 14. From this position, the knitting operation is repeated with the filler thread now laid from right to left as viewed from the rear of the machine. As can be seen, the knitting of the warp thread is not affected by the filler thread which may be variably laid as previously described. It will be remembered that the filler thread need not be laid at every knitting course despite the fact that the carriage 135 moves across with each course of knitting. Hence the previously stated means for obtaining wide variations in the knitted fabric may be more clearly understood.

As seen in Figs. 8 and 14 to 18, inclusive, the sinkers 118 are preferably formed with extended finger portions 118^b so that in any position of said sinkers the filler threads B are suitably supported thereon. However, it is not essential that all of the sinkers be provided with said extended portions so long as a sufficient number of them are provided to prevent sagging of the oncoming filler thread as it is being deposited thereon. In this manner, the filler threads may be deposited directly from the shuttle carriage without the employment of other means for supporting said threads until the sinkers are ready to receive them.

As shown in Fig. 19, a plurality of warp threads may be brought to the knitting course for each needle. This arrangement provides for incorporating into the fabric an unknitted warp thread C. From this view it can be seen that when only the loopers 99 are moved endwise to form the loops A² and the loopers 99^a are not, only those

warp threads A which are carried by said endwise moving loopers are knitted by the needles. The other warp C is therefore unknitted.

One form of material formed in this manner is shown in Fig. 20 and the flexibility of design of fabric, with the further addition of this unknitted warp thread, may be readily imagined. Fig. 21 discloses a knitted or chain-stitch filler D, which may be employed as a filler thread. This knitted filler may be combined with unknitted fillers during the making of the fabric, or any combination of knitted and unknitted warp and/or filler yarns may be incorporated in the fabric by the means heretofore set forth.

It can be readily seen by the above description that a plurality of simultaneously operable carriers may be provided for simultaneously feeding a plurality of filler threads adjacent the needles to respectively incorporate the same in separate fabrics simultaneously produced by the machine. For this purpose warp threads are omitted from the warp feeding guide fingers at predetermined intervals leaving spaces, the width of a fabric produced being fixed by the distance between two successive inactive guide finger spaces. One or more of the filler thread carriers can be made to selectively operate between these successive spaces since the length of the carrier travel may be varied.

While the structural details of the invention as disclosed are at present preferred, it can be well understood that skilled persons may substitute mechanical equivalents therefor without departing from the spirit and scope of the invention as claimed.

Having thus described our invention what we claim as new and desire to be secured by Letters Patent is:

1. In a knitting machine for forming warp and filler threads into a fabric, the combination with knitting elements including a bank of needles, of a longitudinally reciprocable carriage for feeding filler thread substantially parallel to the needle bank, a flexible perforated band for moving said carriage, and filler sinkers movable transversely of the machine for receiving filler thread directly from said carriage, said sinkers being adapted to place said filler thread in position to be incorporated in the courses of the fabric during the knitting operation.

2. In a knitting machine for forming warp and filler threads into a fabric, the combination with knitting implements including a bank of needles, of a longitudinally reciprocable carriage for feeding filler thread substantially parallel to the needle bank, a flexible perforated band for moving said carriage, said carriage comprising a portion removably attached to said band and a carrier portion adapted to be separated from the fixed portion, and filler sinkers movable transversely of the machine for receiving filler thread directly from said carrier portion, said sinkers being adapted to place said filler thread in position to be incorporated in the courses of the fabric during the knitting operation.

3. In a knitting machine for forming warp and filler threads into a fabric, in combination, means for feeding warp thread, means for knitting said warp thread to form a fabric, means for feeding filler thread for incorporation into said fabric, means for reciprocating said filler feeding means, said filler feeding means comprising a carriage attached to said reciprocating means and a filler thread carrier portion, and means for disassociat-

ing said carrier portion from said carriage at either end of the travel of said filler means.

4. In a knitting machine for forming warp and filler threads into a fabric, in combination, means for feeding warp thread, means for knitting said warp thread to form a fabric, means for feeding filler thread, means for reciprocating said filler feeding means, said filler feeding means comprising a carriage attached to said reciprocating means and a filler thread carrier member, means for maintaining said carrier member coupled to said carriage, and means for uncoupling said carrier member from said carriage at either end of the travel of said filler feeding means.

5. In a knitting machine for forming warp and filler threads into a fabric, in combination, means for feeding warp thread, means for knitting said warp thread to form a fabric, means for feeding filler thread for incorporation into said fabric, said filler feeding means including a carriage and a filler thread carrier, means carried by said carriage having engagement with said carrier whereby said carrier may be selectively coupled to or uncoupled from said carriage, and means for actuating said coupling means.

6. In a knitting machine for forming warp and filler threads into a fabric, in combination, means for feeding warp thread, means for knitting said warp thread into said fabric, means for feeding filler thread for incorporation into said fabric, said last-mentioned means comprising a carriage and a pair of filler thread carriers, means carried by said carriage having engagement with said carriers whereby said carriers may be each selectively coupled to and uncoupled from said carriage, and means for actuating such coupling means.

7. In a knitting machine for forming warp and filler threads into a fabric, in combination, means for feeding warp thread, means for knitting said warp thread into a fabric, means for feeding filler thread for incorporation into said fabric, means for reciprocating said filler feeding means, said filler feeding means comprising a carriage secured to said reciprocating means and a filler thread carrier, means for guiding the movement of said carriage, means for guiding the movement of said carrier, and means for uncoupling said carrier from said carriage at either end of the travel of said filler feeding means, whereby the feeding of filler thread is interrupted.

8. In a knitting machine for forming warp and filler threads into a fabric, in combination, means for feeding warp thread, means for knitting said warp thread into a fabric, means for feeding filler thread for incorporation into said fabric, said filler feeding means comprising a carriage and a pair of filler thread carriers, means carried by said carriage having engagement with said carriers, whereby said carriers may be each selectively coupled to or uncoupled from said carriage, and means for actuating said coupling means, said last-mentioned means including cam operated selector means synchronized with the operation of the machine.

9. In a knitting machine for forming warp and filler threads into a fabric, in combination, means for feeding warp thread, means for knitting said warp thread into a fabric, means for feeding filler thread for incorporation into said fabric, said filler thread feeding means comprising a carriage and a pair of filler thread carriers, means carried by said carriage having engagement with said carriers, whereby said carriers may be each selectively coupled to or uncoupled from said carriage, 75

means for actuating said coupling means, said means including cam operated selector means synchronized with the operation of the machine, and an oscillatory member at each end of the travel of said filler feeding means, said oscillatory member being adapted to engage said carriage carried means at each of said ends of travel of said filler feeding means.

10. In a knitting machine for forming warp and filler threads into a fabric, in combination, means for feeding filler thread for incorporation into said fabric, said filler feeding means comprising a carriage adapted to reciprocate continuously during the operation of the machine, a filler thread carrier coupled with said carriage, means for uncoupling said carrier at either end of the travel of said carriage, and means for holding said carrier immovable during its uncoupled condition.

11. In a knitting machine for forming warp and filler threads into a fabric, in combination, filler feed means for incorporating filler thread into said fabric, means for actuating said feed means, and selector means for coupling said feed means with said actuating means, said coupling means including a pair of members and cam means for moving one of said pair of members to one side of a neutral position and for moving the other of said members to the other side of said neutral position.

12. In a knitting machine for forming warp and filler threads into a fabric, in combination, a filler thread feeder, means for reciprocating said feeder including a perforated endless band, a pair of pulleys around which the end bights of the band are trained, means for oscillating one of said pulleys, and brake means associated with one of said pulleys for arresting the movement of said band and said feeder.

13. In a knitting machine for forming warp and filler threads into a fabric, in combination, a filler thread feeder, means for reciprocating said feeder including a perforated endless band, a pair of pulleys around which the end bights of the band are trained, means for oscillating one of said pulleys, means for varying the degree of oscillation of said pulley and thus varying the degree of reciprocatory travel of the feeder, and brake means associated with one of said pulleys for arresting the movement of said band at each end of the travel of said feeder.

14. In a knitting machine for forming warp and filler threads into a fabric, in combination, a filler thread feeder, means for reciprocating said feeder including a perforated endless band, a pair of pulleys around which the end bights of the band are trained, means for varying the degree of travel of said feeder including operating means for oscillating one of said pulleys, and cam means for controlling said operating means.

15. In a knitting machine for forming warp and filler threads into a fabric, in combination, means for feeding warp thread, means for knitting said warp thread to form a fabric, said knitting means including a bank of needles, warp thread looping means, automatic means for controlling the position of said looping means, a longitudinally reciprocable filler feeder for feeding a filler thread substantially parallel to said

needle bank for incorporation into said fabric, flexible means for moving said filler feeder, filler guides movable transversely of said needle bank to position said filler thread for incorporation in courses of the warp during the knitting operation, automatically controlled course selector means for

selecting the courses into which filler threads are incorporated, and coupling means between said warp control means and said filler control means, whereby said filler selector means may be operated at any time during the knitting operation without stopping the machine.

16. In a knitting machine for forming warp and filler threads into a fabric, in combination, a reciprocatory member, a filler feeder for incorporating filler feed into said fabric, said feeder being carried by said member and including at least two feeding members, and at least two auxiliary filler thread feeding members adapted to be moved by said reciprocatory member during intermediate portions of the travel of said filler feeder.

17. In a knitting machine for forming warp and filler threads into a fabric, in combination, a reciprocatory member, a filler feeder for incorporating filler thread into said fabric, said feeder being carried by said member and having at least two filler thread feeding members, at least two auxiliary filler feeding members connected together, and means carried by said reciprocatory member for imparting delayed motion to said auxiliary members during intermediate portions of the travel said filler feeders.

18. In a knitting machine for forming warp and filler threads into a fabric, in combination, warp thread feeding means, warp thread knitting means by which at least two runs of fabric may be simultaneously knitted, means for incorporating a filler thread into each of said fabrics for the entire width thereof, and means for incorporating a filler thread into each of said fabrics for only a portion of the width thereof.

19. In a knitting machine for forming warp and filler threads into a fabric, in combination, warp thread feeding means, warp thread knitting means by which at least two runs of fabric may be simultaneously knitted, a reciprocatory member, a filler feeding member carried by said reciprocatory member and having a filler thread feeder for each run of fabric, means for reciprocating said reciprocatory member, whereby said filler feeding member is traversed a distance greater than the width of each of said fabrics, at least two auxiliary filler thread feeding members connected together, and means carried by said reciprocatory member adapted to move said auxiliary members a distance less than the width of each of said fabrics.

20. In a knitting machine for forming warp and filler threads into a fabric, in combination, means for feeding filler thread for incorporation into said fabric, means for imparting non-uniform reciprocating motion to said feeding means, said feeding means including a carriage attached

5 to said reciprocating means and a filler carrier, and means for dissociating said carrier from said carriage at either end of the travel of said feeding means.

21. In a knitting machine for forming warp and filler threads into a fabric, in combination, a device for feeding filler thread for incorporation thereof into said fabric, means for imparting non-uniform reciprocating motion to said device, said device including a carriage attached to said means and a filler carrier, means for dissociating said carrier from said carriage at either end of the travel of said device, and means for varying the length of travel of said device.

22. In a knitting machine for forming warp and filler threads into a fabric, in combination, a device for feeding filler thread for incorporation thereof into said fabric, said device including a carriage and a pair of filler thread carriers, means carried by said carriage having engagement with said carriers, whereby said carriers may be each selectively coupled to or uncoupled from said carriage, means for actuating said coupling means, and means for varying the length of travel of said device.

23. In a knitting machine for forming warp and filler threads into a fabric, in combination, a warp beam, a plurality of loopers adapted to have threaded therethrough threads from said warp beam, a needle bar having a plurality of needles mounted therein, means for moving said needle bar to reciprocate all of said needles as a unit, means for shifting said loopers transversely of said needles to loop said warp threads about the needles during the knitting operation, a member adapted to reciprocate longitudinally of said needle bar, a plurality of filler thread carrier arms adapted to be coupled to and uncoupled from said member, and means for selectively coupling said arms to and uncoupling said arms from said member to incorporate filler threads as desired with the courses of the fabric knitted by said needles.

24. In a knitting machine for forming warp and filler threads into a fabric, in combination, means for knitting warp threads into a fabric, said means including a bank of needles, a member reciprocable along said needles for incorporating into said fabric a filler thread throughout substantially the entire width of the fabric, means for reciprocating said member, a reciprocable member for incorporating another filler thread in an intermediate portion of the fabric, means for reciprocating said second member, and means for selectively operating said members.
